(No Model.)

J. WORTHINGTON.
DOUBLE CYLINDER PUMP.

No. 580,479.

Patented Apr. 13, 1897.

UNITED STATES PATENT OFFICE.

JAMES WORTHINGTON, OF MANITOWOC, WISCONSIN, ASSIGNOR OF ONE-HALF TO THEODORE C. SHOVE, OF MINNEAPOLIS, MINNESOTA.

DOUBLE-CYLINDER PUMP.

SPECIFICATION forming part of Letters Patent No. 580,479, dated April 13, 1897.

Application filed June 1, 1896. Serial No. 594,176. (No model.)

To all whom it may concern:

Be it known that I, JAMES WORTHINGTON, of the city of Manitowoc, Manitowoc county, State of Wisconsin, have invented certain new and useful Improvements in Double-Cylinder Pumps, of which the following is a specification.

This invention relates to improvements in double-cylinder pumps; and the objects I have in view are to provide a double-cylinder pump in which both cylinders are located in the same axial line, or one above the other, with a casing or casings surrounding the same, with provision for the water or liquid passing around the lower cylinder and entering the lower end of the upper cylinder, while the liquid that passes into the lower end of the lower cylinder passes out at the upper end of that cylinder and then passes outside of the upper cylinder, both the water from the lower and from the upper cylinder coming together in a pipe or reducer above the upper cylinder.

The invention consists generally in the construction and combination hereinafter described, and particularly pointed out in the claims.

In the accompanying drawings, forming part of this specification, Figure 1 is a vertical section of a double-cylinder pump embodying my invention. Fig. 2 is a horizontal section on line 2 2 of Fig. 1. Fig. 3 is a horizontal section on line 3 3 of Fig. 1. Fig. 4 is a horizontal section on line 4 4 of Fig. 1. Fig. 5 is a detail showing a modified manner of securing the two casings together.

In the drawings, 2 2 represent the outer casings, which are of the same size and arranged in the same axial line. A single casing might be employed, but for convenience in putting the pump together I prefer to use the two casings arranged as shown.

At the lower end of the lower casing is secured a reducer 3, to which is secured the supply-pipe of both cylinders, and at the upper end of the upper cylinder is a reducer 4, which connects with the service-pipe in both cylinders. Suspended within the casings 2 are the two cylinders 5 and 6, arranged one above the other. The lower casing is provided at its lower end with a cylinder-head 7,

provided with a suitable inlet-valve 8, and this cylinder is provided with a piston 9, secured upon the piston-rod 10 and provided with a suitable valve 11. Secured to the upper end of the lower cylinder and to the walls of the casings is the head 12. The ends of both casings are preferably secured to the outer wall of the head 12, as shown in Fig. 1, as by soldering or other suitable means. I may, however, form screw-threads upon the ends of the casings and connect them by a threaded ring 13, as shown in Fig. 5. Therefore I do not limit myself to any particular means for securing the ends of the casings to the head 12. The head 12 is provided with the two ports 14, through which the liquid flows from the lower cylinder into the space between the upper cylinder and the surrounding casing. The head 12 is also provided with a double port 15, which extends from the top of the lower cylinder to the central opening in the head 16 of the upper cylinder. Said upper cylinder is provided with a suitable valve 17.

The upper cylinder is provided with a piston 18, valve 19, and a hollow piston-rod 21, that surrounds the piston-rod 10 of the lower cylinder. At the upper end of the upper cylinder is arranged a head 22, to which the upper end of said cylinder is secured, said head also being secured to and forming a head for the casing 2. The head 22 is provided with two ports, the port 23 leading from the upper cylinder into the reducer 4 and the port 24 leading from the space surrounding the cylinder 5 into the reducer 4. Said ports are provided with suitable valves 25.

The operation of the device is as follows: The liquid for both cylinders passes through the reducer 3 and a part of it passes through the valve 8 into the lower cylinder. Another part of the liquid passes around the cylinder 6 and through the port 15 into the lower part of the upper cylinder. The piston-rods are moved so as to alternate with each other, so that if one piston is moving up the other is moving down. The liquid from the lower cylinder passes up around the space outside of the cylinder 5 and the liquid from the upper cylinder passes through the port 23 and into the space above the valve 25. By this means

a constant and steady flow of liquid is produced.

5 The pump is simple and inexpensive in construction and can be used in any place where a single-cylinder pump can be used. The cylinders can be easily removed for the purpose of repairing the valves or for any other purpose, and all of the parts of the pump are of the simplest and most inexpensive form.

10 Having thus described my invention, I claim as new and desire to secure by Letters Patent—

15 1. The combination, with a suitable casing, of two cylinders arranged therein, a head arranged between said cylinders and connected to said casing, said head being provided with ports connecting the interior of each cylinder with the space surrounding the other cylinder, a piston in each cylinder, and means for 20 operating said piston.

20 2. The combination, with the casing 2, of the cylinders 5 and 6 suspended therein, each of said cylinders being provided at its lower

end with a head having a suitable valve, the head 12 arranged between said cylinders and 25 connected to said casing, and provided with the ports 14 and 15 arranged as described, the pistons arranged in said cylinders, and the head 22 connected to said casing and to the upper end of the upper cylinder, and provided with the ports 23 and 24.

3. In a pump, the combination, with a suitable casing, of two cylinders arranged therein, one above the other, a space being provided between the outer wall of each cylinder and the inner wall of said casing, means connecting the interior of each cylinder with the space outside of the other cylinder, and a suitable piston in each cylinder.

35 In testimony whereof I have hereunto set 40 my hand this 18th day of May, A. D. 1896.

JAMES WORTHINGTON.

In presence of—

H. L. MARKHAM,
B. E WILCOX.
